UNITED STATES PATENT OFFICE

HENRY E. STEVENS, OF JACKSONVILLE, FLORIDA, ASSIGNOR TO DOROTHY A. STEVENS,
OF NEW YORK, N. Y.

BUILDING TILE

Application filed May 1, 1930, Serial No. 449,033. Renewed October 6, 1932.

The ordinary building tile is difficult to lay rapidly because its rough, wire-cut ends tear the hands and its bulk is such that it must be grasped with two hands. Various ways 5 have been devised to make a tile that can be carried by one hand. It is the purpose of my invention to secure this result in a better way than has been done heretofore, both in regard to economy in production and greater 10 ease of handling. The prior devices of this type have all been designed to provide a handle which could be grasped by the fingers and thumb, for which purpose two parallel slots were made in one or more walls of the tile on 15 opposite sides of one of the inner webs. In some cases narrow ledges were made to facilitate the grasping.

According to my invention the tiles are not provided with a handle to be grasped, but a 20 single hole is made to receive the fingers only and this hole is so located that the fingers can be flexed to extend under an upper wall of the tile about at its center of balance, the under surface of the upper wall being unob- 25 structed for a considerable distance from the opening to allow the fingers to be so inserted and flexed. By "considerable distance" I mean a distance substantially greater than the distance from the end of a 30 man's middle finger to the first joint or articulation, so that the fingers can be flexed at the middle joint and extend under the upper wall far enough to have the edge of the hole come about half way between the termi- 35 nal and intermediate joints or beyond. For the average man's fingers the distance across this unobstructed surface should be about one and one half inches. This makes it unnecessary to grasp the tile; in fact, a tile 40 which rests with this broad surface on the fingers can be carried with greater ease and comfort than one having narrow ledges which must be grasped. The upper wall being ordinarily of the same thickness as the 45 other walls, namely not more than a few eighths of an inch, it is not necessary to insert the hand beyond the base of the fingers; con-sequently the knuckles at this point are not in danger of being scratched by the edge of the hole. Also the fingers are thinner than

the hand at the palm and a narrower hole will admit them than would be required for a deeper insertion of the hand. A smaller hole means less weakening of the tile and less warping during burning. 55

In speaking of the center of balance of the tile I refer to that point in the plane of the upper wall of the tile which lies directly above the center of gravity of the tile when the latter is in the position it will assume 60 when embodied in a vertical wall.

In the drawings I have shown several forms of the invention by way of example.

Fig. 1 is a perspective view of one standard form of tile with my invention applied 65 to it.

Fig. 2 is a transverse section through a portion of the tile shown in Fig. 1, including the hole, and showing a left hand in position to lift the tile. 70

Fig. 3 is a perspective view of another standard form of tile showing my invention applied in a slightly different way, 75

Fig. 4 is a perspective view of a tile similar to that shown in Fig. 1, but with my invention applied in still a different way, 80

Fig. 5 is a perspective view of a narrow tile showing how the hand hole can be applied to a vertical wall at the height of the lower surface of the top wall, 85

Fig. 6 is a transverse section through a portion of the tile shown in Fig. 5, including the hole and showing a left hand in lifting position. 90

The tile shown in Fig. 1 is composed of vertical outside walls 1, vertical intermediate webs 2, a top wall 3 having depressed middle portion 4, a bottom wall 5, and horizontal reinforcing webs 6. In the depressed portion of the top wall is an elongated hole 7 arranged with its long axis parallel to the webs of the tile. As shown in Fig. 2, this hole is adapted to receive the fingers of a man's hand, which can be extended under the broad lower surface of the wall 4. The fingers support the tile substantially at its center of balance and the breadth of the supporting surface makes it unnecessary to grasp the wall. The tile can therefore be carried 100

with the greatest possible ease and without tiring the mason's hand.

Fig. 3 shows a tile similar to Fig. 1 except that the middle portion 4 of the upper wall is not depressed, a horizontal web 8 is added in the middle portion, and the hole 7 is arranged transversely and slightly to one side of the center of balance of the tile, so that when the fingers are inserted and directed toward the longer section of the tile they will come under the center of balance.

In many cases it will be desirable to have the hole at the center of balance of the tile so that the fingers can be inserted in either direction and still have the support come near enough to the center of balance for practical purposes. Such a tile is shown in Fig. 4. If necessary, this tile can be perfectly balanced by a light pressure of the thumb on the top.

Figs. 5 and 6 show how the object of my invention can be secured with a narrow tile by arranging the hole in one of the vertical walls so that its upper edge comes substantially flush with the lower surface of the upper wall 3. In this case the fingers can be inserted full length under the upper wall and thereby rest substantially under the center of balance of the tile.

Various modifications within the scope of my invention will occur to those skilled in the art. I have illustrated its application to several standard forms of tile, but it can be applied equally well to many others, so long as the construction does not interfere with the essential feature that the hole is arranged so that the fingers can extend under the top wall and support the tile substantially at its center of balance, the lower surface of the top wall being for this purpose unobstructed for a distance from the hole which will permit the fingers to be flexed to extend under the upper wall far enough to bring the edge of the hole about halfway between the terminal and intermediate joints or beyond. The unobstructed surface may, of course, be still longer. In the case of a reversible tile there may be a plurality of independent holes each arranged so that the fingers can be inserted under any wall which may be a top wall, and narrow tiles may have holes at each side, as shown in Fig. 6. Tiles having holes in two opposite walls can be picked up easily no matter what side or end they are lying on.

Having described my invention, I claim:

1. A building tile comprising walls defining one or more voids, one of said walls having a hole therein of such size and conformation as to permit the insertion of a man's fingers, said hole being located so as to permit the fingers to be flexed to extend along the lower face of an upper wall of said tile adjacent the center of balance thereof, said lower face being unobstructed for a distance of about one and one half inches or greater from said hole to permit the fingers to be so inserted

and flexed, to contact the upper wall and support the tile by said flexed fingers.

2. A building tile comprising walls defining a plurality of voids, an upper wall of said tile having a hole therein located at the center of balance of the tile, the lower surface of said upper wall being unobstructed on each side of said hole for a distance substantially greater than the distance from the end of a man's middle finger to the terminal joint to permit the fingers to be inserted and flexed to contact said upper wall and support the tile by said flexed fingers.
